UNITED STATES PATENT OFFICE.

HERBERT R. MATSCHULL AND OSCAR FROHMAN, OF MILWAUKEE, WISCONSIN, ASSIGNEES TO KOEHRING COMPANY, OF MILWAUKEE, WISCONSIN, A CORPORATION.

BALANCED VALVE.

Application filed October 17, 1923. Serial No. 669,077.

To all whom it may concern:

Be it known that we, HERBERT R. MATSCHULL and OSCAR FROHMAN, citizens of the United States, residing at Milwaukee, in the county 5 of Milwaukee and State of Wisconsin, have invented certain new and useful Improvements in Balanced Valves, of which the following is a specification.

Under practical conditions of use it is 10 customary to employ in conjunction with concrete mixers, a water tank adapted to supply the mixer with a charge of water proportioned to the quantity of solid aggregates to be handled in the machine. The water 15 supply tank, or reservoir, is in turn supplied with water from a main pipe line that leads to a suitable source of water; valve means are usually provided to control passage of the water from the main supply pipe line to the 20 tank, and from the tank to the mixer.

The present invention proposes a novel 25 value means of the type just referred to, consisting of a three-way valve mechanism, involving a pressure balanced valve that employs no metal to metal contacting parts 30 whatever. The metal to metal seating valve, such as a plug valve, that has been most commonly used heretofore, has proved inefficient, owing to the fact that it becomes worn out so quickly and makes very difficult 35 replacement or repairing, which may become necessary at most inopportune moments in the operation of a large mixing plant dependent upon efficient water supply control means.

The novel features of the present invention 40 reside primarily in utilizing a three-way valve under peculiar manual and automatic control; the provision of a special construction of the valve and a counter balancing piston so arranged in a valve casing as to be bodily displaceable therefrom in a minimum amount of time, and by the operation of very few parts; certain provisions whereby the 45 movement of the valve is rendered very quick in action so that accurate measuring of the water delivered by the operation of the valve may be insured; together with other detailed provisions, the advantages of which will appear quite fully on reference to the appended 50 description.

In the accompanying drawings,

Figure 1 is a general view somewhat in elevation of the three-way valve mechanism, 55 with its manual and automatic operating

contrivances and water pipe arrangements illustrated in full lines, and certain parts of a concrete mixing machine to which the same may be applied, illustrated in dotted lines.

Figure 2 is a top plan view of the main 60 valve mechanism features and operating parts, seen in Figure 1, the mixer features being omitted from the illustration.

Figure 3 is an enlarged top plan view 65 showing more particularly the valve casing and the operating contrivances therefor, the automatic operated arm being shown in section at its axis, and the manual actuated arm for opening the valve being omitted.

Figure 4 is a vertical sectional view 70 through the valve casing and adjacent parts of the valve mechanism, the dotted lines showing extremes of shifting movement of the valve lifting lever and the arrangement of the parts, when they are moved from a 75 position in which the valve is open to a position in which it is closed.

Referring to Figure 1 of the drawings, the concrete mixing drum is designated A, the supporting frame work B, and the loading skip at C, said skip being illustrated in 80 several positions to show how the pin or lug 1 thereof, engages the lower end of the actuating bar 2, by which the valve of the invention is opened automatically on the rising movement of the skip, as will appear 85 more fully hereinafter.

On the upper portion of the framework B is mounted a valve casing 3 which is equipped with a pipe 4 that leads laterally from its 90 middle portion to the measuring water tank not shown. Said water tank would be located on the framework B just above the lefthand end of the pipe 4, were there room in Figure 1 to illustrate it; said water tank would also 95 be provided with a measuring valve by which to determine the quantity of water to be fed to the mixer drum A. Since the measuring valve is well known in the art of concrete mixing machines, and is well exemplified by 100 the construction presented in the U. S. Letters Patent of Koehring No. 1,149,922, issued August 10, 1915, no showing of this particular valve is made herewith as different types of such valve might be employed 105 any way within the purview of the invention. There leads from the lower end of the casing 3 downwardly an out flow pipe 5 that extends to the mixer drum, having its lower end extending to the left, as shown at 5' in 110

Figure 1 so as to enter the mouth, or charging opening of the drum. Connected with the upper end portion of the casing 3 is the water supply pipe 6, having its lower portion 6' leading downwardly and off to any suitable point of connection with the main pipe line that forms the source from which a suitable head of water is lead to the mixing machine. As the pressure in the pipe line varies greatly under actual conditions of service ranging from 25 pounds to 250 pounds, the desirability of a balanced valve mechanism for controlling the passage of water with such a pressure, will be quite obvious.

At its upper end the pipe 6 leads, as shown at 6" to the casing 3, and is suitably attached thereto so that water from the pipe 6 may flow into the upper end portion of the casing.

The valve device itself, may now be described on reference particularly to Figure 4, wherein are seen the middle valve chamber 7, the lowermost, or out flow chamber 8, and the uppermost inflow chamber 9. At its middle portion, or section, the casing 3 is equipped with the opposing valve seats 10 and 11, the lower valve seat being carried by an annular web 10^a integral with the casing 3, and the upper valve seat 11 being formed at the lower end of a removable cylinder 12, mounted in the upper portion of the valve casing 3. The cylinder 12 is formed with an annular shoulder 13 that rests upon a similar shoulder 14, projecting from the wall of the casing 3 at its middle portion. The cylinder 12 has mounted therein the counter-balancing piston 15 through which passes the stem, or piston rod 16 suitably screwed or otherwise applied to the piston itself, the lower end of said rod 16 having a pivotal connection, as shown at 17 with the stem 18 of the three-way valve 19 which is mounted between the seats 11 and 10. The valve has a downwardly projecting stem 20 which passes through a guiding yoke, or spider, 21, that is formed as a part of the valve seat, or ring 10. In its circular wall the cylinder 12 is formed with openings 22 that enable the water passing into the upper portion of the cylinder portion of the casing 3, to pass on downwardly through said openings to the middle chamber 7 of the casing 3 when the valve 19 is in the position of Figure 4.

At its upper end, the cylinder 12 is formed with a centering annular shoulder 12^a that fits snugly into the casing 3, and there is applied to the casing 3 a cap, or cover plate, 23, seen best in Figure 3 as comprising a body having three outstanding or diverging lugs 24 through which bolts 25 pass, said bolts also passing through openings in lugs 26 off-standing from the upper end of the casing 3. It is notable however, that the rod or

stem 16 passes through a central opening in the cover plate 23 and the need of a packing box at the opening, is obviated, owing to the provision of the packing 27 acting between the plate 23 and the internal removable cylinder 12.

It should be particularly observed that the valve 19, and its removable seat 10 are of a diameter less than the diameter of the opening in the casing 3 at the shoulder 14; 75 the reason for this is to enable removal of the valve and the part 10 upwardly through the casing when desired. Furthermore, it is clear from the construction as illustrated, that when the cover plate 23 is detached 80 from the casing 3, the cylinder 12 with its packing 27 and the valve 19 may be removed as a unit. A gasket 29 may be located between the shoulder 13 of the cylinder 12 and the shoulder 14 of the casing 3, and said gasket may be readily renewed when the parts 12 and 19 are removed, and if necessary, the seat 10 is accessible for its removal, something however, which would hardly ever be necessary because the piston 90 19 is provided with rubber seats for engagement with the seats 10 and 11 respectively of the parts 3 and 12 respectively.

Operating means for the valve 19 may now be set forth and consists of a lever 30 pivoted to a bracket arm 31 on the cover plate 23, said lever having a loose pin and slot connection at 32 attaching it to the upper end of the stem or rod 16. At its free end the lever 30 has pivotal connection at 33 with a link 34, that extends downwardly at one side of the casing 3, and is connected by a cross pin 35 with a throw-over lever 36 pivoted at 37 to the outer end of a bracket 38, which projects laterally from the casing 3 and may preferably be integral therewith. The throw-over lever 36 embodies spaced sides and a cross head 36^a, and has connection by bolts 40 at its end with springs 41 attached at the ends opposite the bolts 40 to a rock shaft 42. The attachment means between the shaft 42 and the springs consists of small plates 43 freely pivoted on the rock shaft in a loose manner. The shaft 42 is mounted in suitable bearings on the bracket 38 parallel with the axis 37 of the throw-over lever 36, and said shaft 42 carries a pair of curved arms 44, which are keyed to the shaft, as shown at 45 so that when the shaft is rocked the said arms may move 110 the lever 36 up or down dependent upon the direction of rocking. This result is obtained because the outer arcuate moving ends of the arms 44 are connected to the sides of the lever 36 by means of the cross pin 35 that forms the attachment means between the link 34 and said lever 36, the said pin 35 passing through slots 36^b in the said sides of the lever 36. Mounted on one end of the rock shaft 42 is the operating arm 46 which 115 120 125 130

is loose on the shaft, but has a lug 47 extending from its hub portion to engage with a collar 48 keyed to the shaft 42, as shown at 49.

5 The outer moving end of the arm 46 is attached to the actuating bar 2 at the upper end of the latter. The bar 2, it will be remembered, is capable of being shifted upwardly by the pin 1 on the skip C, and this 10 movement is relied upon for an automatic opening of the valve 19 to be shortly described quite fully. The bar 2 is guided in its up and down movement by a guiding yoke 50, between the sides of which may be 15 mounted a roller 51 on which the bar 2 rests and moves easily. The bar 2 furthermore, is made in sections including the uppermost clevis member 2^a directly attached to the arm 46, the part 2^a having screw threaded 20 connection with the body of the bar 2 so that there may be an adjustment between these parts whenever desired to shorten or elongate the bar 2, shortening effecting a 25 delay in the time of opening the valve, and therefore the passage of the water to the mixing drum, and elongating resulting in an advancing of such time of action for obvious reasons.

Connected with the rock shaft 42 at the 20 end opposite that having the arm 46 thereon, is mounted the operating arm 52 suitably keyed or affixed on the shaft 42, and being connected by a rod 53 with a manually operable lever 54 pivoted to the framework 5 of the machine. The purpose of the lever 54 will be apparent hereafter.

With the construction of the machine disclosed as above the operation of the same will be now set forth.

It will be assumed that the valve parts are in the position of Figure 4, that is, water has been supplied to the measuring tank through the pipe 4, and said tank is full and ready to supply the mixer. Under 5 these conditions water fills the chamber 7, pipe 4, the water tank (not shown), the upper end of the casing 3, in fact all of the casing above the valve 19. The pressure of the water acts with counter-balancing effects 10 upwardly against the piston 12, and downwardly upon the top of the valve 19. Under these conditions, the expense of comparatively little power is required in order to open the valve 19 by an upraising action.

It is next assumed that the mixer will now be charged by the skip C, which is raised in the customary manner of operation of these parts of concrete mixing machines, and as said skip rises to supply the solid 15 aggregates to the mixing drum A the actuating bar 2 moves upwardly. At a certain time in the rocking movement of the lever 46, caused by said bar 2, the lug 47 cooperates with the collar 48 on the shaft 42 to 20 rock the shaft 42 and raise the curved arms

44 thereof. This action results in lifting the link 34 and correspondingly raising the piston 12 and the valve 19. As soon as the link 34 and the lever 36 is raised from a position as shown in Figure 4 in full lines 70 to one in which the pivot pin 35 is above a line intersecting the axes 37 and 42, it will be clear that the springs 41 will throw the lever 36 over the dead center, or rather, quickly move it above the dead center point 75 so as to effect a quick action of closing the valve 19 against the seat 11. Under these conditions the supply of water is cut off from the upper piston chamber of the casing 3, and the pipe 6, and the chamber 7 is 80 opened to the chamber 8 to permit the water to flow from the measuring tank through the chambers 7 and 8, below the valve 19, and through the pipe 5 into the mixing drum A. Should it be that the operator desires 85 to admit a little extra water into the mixing drum A, in a quantity greater than that permitted by the measured amount that flows from the tank, the manual lever 54 may be actuated to rock the shaft 42 clockwise slightly, open the valve 19 and let water pass directly from the chamber 9 to the chamber 8.

The foregoing condition does not often 90 arise, but might under practical conditions 95 of service.

As regards the further operation of the valve 19 to assume its normal position, it will be seen from Figure 1 that the skip C may be lowered, and the arm 46 in such 100 operation will move downwards with the actuating or trip bar 2, without affecting the shaft 42. As soon as the water has passed from the measuring tank into the mixing drum, the operator will actuate the 105 lever 54 and throw the arms 44 and the lever 36 back to their original positions of full lines in figure 4. This action closes communication between the pipe 4 and the chamber 7, with respect to the outlet chamber 8, and thereupon the flow of water will 110 pass from the main supply pipe 6 into the chamber 9 of the casing 3, through the openings 22 into the chamber 7 above the valve 19, and on through the pipe 4 to the measuring tank. The latter is thus refilled ready 115 for another charging operation to supply the liquid aggregate of a batch of concrete in the mixing drum A.

It is notable that the springs 41 are preferably under practically little, or no tension when the lever 36 is in either of its extreme positions. Their tension however, is increased to an operative tension for the purposes described, as the lever 36 approaches a central position in line with the axes 37 and 42, which is practically the dead center point of movement of said lever. When the lever 36 is moving upwards, or downwards, past said center point, the action of the 120 125 130

springs 41 is the same in effecting a quick final seating movement of the valve 19.

By merely disconnecting the pivot part 33 to detach the link 34 from the lever 30, 5 and removing the three bolts 25, the operator is enabled to lift on the parts 30 and 23 and withdraw the counter-balance piston 15, the cylinder 12, the valve 19, and the directly attached parts, from within the casing 3, all practically as a removable unit structure.

Having thus described our invention what we claim as new and desire to secure by Letters Patent is,

15. 1. In a three-way valve mechanism of the class described, in combination, a valve casing, a valve movably mounted therein, a cylinder removably mounted in said casing, a counter-balancing piston mounted in said 20 cylinder and connected with the valve, means external to the casing for operating the piston and thereby operating the valve, and means supporting the piston, valve, and cylinder parts on the casing so as to permit their 25 removal as a unit from the casing.

2. In a three-way valve mechanism of the class described, in combination, a valve casing, a valve movably mounted therein, a cylinder removably mounted in said casing, a 30 counter-balancing piston mounted in said cylinder and connected with the valve, means external to the casing for operating the piston and thereby operating the valve, means supporting the piston, valve, and cylinder 35 parts on the casing so as to permit their removal as a unit from the casing, the operating means for the piston including a piston rod, a coverplate above to the casing and through which said rod passes, together with 40 a packing between said coverplate and said cylinder, and the casing substantially as described.

3. In a valve mechanism of the class set forth, in combination, a valve casing provided with a valve seat therein, and also provided with a supporting shoulder, a cylinder mounted on the casing and engaging said shoulder, a valve mounted in the casing and movable to and from said seat, a piston 50 operating in said cylinder and connected with the valve, and means holding the cylinder, its piston, and said valve on the casing but permitting their bodily removal from the casing.

55. 4. In a valve mechanism of the class set forth, in combination, a valve casing provided with a valve seat therein, and also provided with a supporting shoulder, a cylinder mounted on the casing and engaging said shoulder, a valve mounted in the casing and movable to and from said seat, a piston operating in said cylinder and connected with the valve, means holding the cylinder, its piston, and said valve on the casing but 60 permitting their bodily removal from the

casing, the cylinder aforesaid being provided with a seat for the valve, and said cylinder being spaced from the casing and formed with openings at its sides, a supply opening in the portion of the casing surrounding the cylinder for conducting a fluid to the casing to pass through the openings in the cylinder and past the valve, when said valve is unseated from the seat on the cylinder.

5. In a valve mechanism of the class set forth, in combination, a valve casing having a bottom outflow opening, a middle valve chamber adapted to have communication with a measuring tank and provided also with a fluid supply opening at its upper portion above said chamber, said casing being formed with a shoulder at the upper end of said chamber of a diameter greater than the valve hereafter mentioned, a valve disposed in the valve chamber of the casing and adapted to be moved past the shoulder aforesaid, the casing having a valve seat at the bottom of said valve chamber on which said valve is adapted to seat at its underside, a cylinder disposed in said casing in spaced relation to the latter and opposite said supply opening, and having a seat adjacent to said shoulder against which the valve is adapted to seat at its upper side, a piston in said cylinder connected with said valve, and means external to the cylinder and casing for operating the piston, and thereby operating the valve, the cylinder having openings below the piston and between it and the valve establishing communication between the space around the cylinder and the valve chamber aforesaid.

6. In a valve mechanism of the class set forth, in combination, a valve casing having a bottom outflow opening, a middle valve chamber adapted to have communication with a measuring tank and provided also with a fluid supply opening at its upper portion above said chamber, said casing being formed with a shoulder at the upper end of said chamber of a diameter greater than the valve hereafter mentioned, a valve disposed in the valve chamber of the casing and adapted to be moved past the shoulder aforesaid, the casing having a valve seat at the bottom of said valve chamber on which said valve is adapted to seat at its underside, a cylinder disposed in said casing in spaced relation to the latter and opposite said supply opening, and having a seat adjacent to said shoulder against which the valve is adapted to seat at its upper side, a piston in said cylinder connected with said valve, means external to the cylinder and casing for operating the piston, and thereby operating the valve, the cylinder having openings below the piston and between it and the valve establishing communication between the space around the cylinder and the valve chamber aforesaid, and a closing means for

the casing removable to permit removal of the cylinder.

7. In a valve mechanism of the class set forth, in combination, a valve casing having a bottom outflow opening, a middle valve chamber adapted to have communication with a measuring tank and provided also with a fluid supply opening at its upper portion above said chamber, said casing being formed with a shoulder at the upper end of said chamber of a diameter greater than the valve hereafter mentioned, a valve disposed in the valve chamber of the casing and adapted to be moved past the shoulder aforesaid, the casing having a valve seat at the bottom of said valve chamber on which said valve is adapted to seat at its underside, a cylinder disposed in said casing in spaced relation to the latter and opposite said supply opening, and having a seat adjacent to said shoulder against which the valve is adapted to seat at its upper side, a piston in said cylinder connected with said valve, means external to the cylinder and casing for operating the piston, and thereby operating the valve, the cylinder having openings below the piston and between it and the valve establishing communication between the space around the cylinder and the valve chamber aforesaid, and a coverplate for the casing engaging and holding the cylinder in place therein and detachable to permit removal of the cylinder and the valve with which it is connected.

8. In a valve mechanism of the class described, in combination, a valve casing, a cylinder arranged in said casing and removable therefrom, and provided at its lower end with a valve seat, the casing having a valve seat spaced from that of the cylinder, a valve disposed in the casing and operating between the two valve seats above mentioned, a piston in the cylinder having connection with the valve, and a coverplate applied to the casing and engaging said cylinder to hold it in place in the casing, but permitting removal of the cylinder with its piston and the said valve, and means for operating the piston and valve parts.

9. In a valve mechanism of the class described, in combination, a valve casing, a cylinder arranged in said casing and removable therefrom, and provided at its lower end with a valve seat, the casing having a valve seat spaced from that of the cylinder, a valve disposed in the casing and operating between the two valve seats above mentioned, a piston in the cylinder having connection with the valve, a coverplate applied to the casing and engaging said cylinder to hold it in place in the casing, but permitting removal of the cylinder with its piston and the said valve, means for operating the piston and valve parts, includ-

ing a rod passing through the coverplate aforesaid, and actuating means for said rod, together with packing interposed between the coverplate and the cylinder to establish a fluid tight connection there between.

10. In a valve mechanism as set forth, in combination, a casing provided at its lower portion with a valve seat, a cylinder removably fitted in the upper portion of the casing and having a valve seat at its lower portion, a valve disposed in the casing and operating on said seats according to adjustment, a detachable coverplate for the casing coacting to prevent displacement of said cylinder therefrom, a piston in said cylinder connected with said valve, and operating means for the piston valve, the valve being removable from the casing with the said cylinder and piston.

11. In a valve mechanism as set forth, in combination, a casing provided at its lower portion with a valve seat, a cylinder removably fitted in the upper portion of the casing and having a valve seat at its lower portion, a valve disposed in the casing and operating on said seats according to adjustment, a detachable coverplate for the casing coacting to prevent displacement of said cylinder therefrom, a piston in said cylinder connected with said valve, operating means for the piston valve, the valve being removable from the casing with the said cylinder and piston, the operating means for the piston and valve comprising a rod extending to a point external to the casing, a lever connected with said rod, a second throw-over lever connected with the first lever and movable to shift the valve from one of its seats to the other, and spring means cooperating with the throw over lever to effect a quick action of the latter, and corresponding quick movement of the valve when said valve passes a point substantially midway of its extremes of movement.

12. In a valve mechanism as set forth, in combination, a casing provided at its lower portion with a valve seat, a cylinder removably fitted in the upper portion of the casing and having a valve seat at its lower portion, a valve disposed in the casing and operating on said seats according to adjustment, a detachable coverplate for the casing coacting to prevent displacement of said cylinder therefrom, a piston in said cylinder connected with said valve, operating means for the piston valve, the valve being removable from the casing with the said cylinder and piston, the operating means for the piston and valve comprising a rod extending to a point external to the casing, a lever connected with said rod, a second throw-over lever connected with the first lever and movable to shift the valve from one of its seats to the other, spring means cooperating with

- the throwover lever to effect a quick action of the latter, and corresponding quick movement of the valve when said valve passes a point substantially midway of its extremes 5 of movement, said spring means comprising a spring attached to a free swinging end of the said mentioned lever and also attached to a point of attachment which is eccentric of the pivot of said second lever, whereby 10 the spring acts to shift the lever quickly when it passes a dead center point of its movement as regards the point of spring connection in its relation to the axis of the lever.
- 15 13. In a valve mechanism as set forth, in combination, a valve casing, means for supplying a fluid from said casing to a mixing drum, a main water supply pipe connected with the upper portion of the valve casing, 20 a measuring tank water conducting pipe leading from the casing, a valve mounted in said casing to control passage of water through the casing to the mixing drum from a measuring tank, and to control passage of 25 water from the main water supply pipe through the casing to the measuring tank, and means for operating said valve comprising a lever external to the casing connected to the valve, a throw-over lever linked to said first lever, spring means for compelling accelerated movement of the throw over lever after its movement has been initiated a 30 predetermined extent, a rock shaft for initiating the movement of the throw-over lever operatively connected thereto, means whereby movement is imparted to the shaft, and a manual lever controlling the operation of 35 said rock shaft to restore the valve to a normal original position after actuation.
16. In a valve mechanism as set forth, in combination, a valve casing, means for supplying a fluid from said casing to a mixing drum, a main water supply pipe connected with the upper portion of the valve casing, a measuring tank water conducting pipe leading from the casing, a valve mounted in said casing to control passage of water 40 through the casing to the mixing drum from the measuring tank, and to control passage of water from the main water supply pipe through the casing to the measuring tank, and means for operating said valve comprising a lever external to the casing connected to the valve, a throw-over lever linked to 45 said first lever, spring means for compelling accelerated movement of the throw-over lever after its movement has been initiated a predetermined extent, a rock shaft for initiating the movement of the throw-over lever operatively connected thereto, means whereby movement is imparted to the shaft, a manual lever controlling the operation of 50 said rock shaft to restore the valve to a normal original position after actuation by the skip, a loose connection intermediate the movement imparting means and the rock shaft, whereby the said movement imparting 55 means may move independently of the rock shaft, said manual means being operable to actuate the valve partially independently of its full restoration to a normal original position.
17. In a valve mechanism as set forth, in combination, a valve casing, means for supplying a fluid from said casing to a mixing drum, a main water supply pipe connected with the upper portion of the valve casing, a measuring tank water conducting pipe leading from the casing, a valve mounted in said casing to control passage of water 60 through the casing to the mixing drum from the measuring tank, and to control passage of 65 water from the main water supply pipe through the casing to the measuring tank, and means for varying the extent of movement of the last mentioned means, to control the time of operation of the rock shaft.
18. In a valve mechanism as set forth, in combination, a valve casing, means for supplying a fluid from said casing to a mixing 70 drum, a main water supply pipe connected with the upper portion of the valve casing, a measuring tank water conducting pipe leading from the casing, a valve mounted in said casing to control passage of water through the casing to the mixing drum from a measuring tank, and to control passage of water from the main water supply pipe through the casing to the measuring tank, and means for operating said valve comprising a lever external to the casing connected to the valve, a throw-over lever linked to said first lever, spring means for compelling accelerated movement of the throw over lever after its movement has been initiated a 75 predetermined extent, a rock shaft for initiating the movement of the throw-over lever operatively connected thereto, means whereby movement is imparted to the shaft, and a manual lever controlling the operation of 80 said rock shaft to restore the valve to a normal original position after actuation.
19. In a valve mechanism as set forth, in combination, a valve casing, means for supplying a fluid from said casing to a mixing drum, a main water supply pipe connected with the upper portion of the valve casing, a measuring tank water conducting pipe leading from the casing, a valve mounted in said casing to control passage of water 85 through the casing to the mixing drum from the measuring tank, and to control passage of water from the main water supply pipe through the casing to the measuring tank, and means for operating said valve comprising a lever external to the casing connected to the valve, a throw-over lever linked to said first lever, spring means for compelling accelerated movement of the throw-over lever after its movement has been initiated a predetermined extent, a rock shaft for initiating the movement of the throw-over lever operatively connected thereto, means whereby movement is imparted to the shaft, a manual lever controlling the operation of 90 said rock shaft to restore the valve to a normal original position after actuation.
20. In a valve mechanism as set forth, in combination, a valve casing, means for supplying a fluid from said casing to a mixing drum, a main water supply pipe connected with the upper portion of the valve casing, a measuring tank water conducting pipe leading from the casing, a valve mounted in said casing to control passage of water 95 through the casing to the mixing drum from the measuring tank, and to control passage of water from the main water supply pipe through the casing to the measuring tank, and means for operating said valve comprising a lever external to the casing connected to the valve, a throw-over lever linked to said first lever, spring means for compelling accelerated movement of the throw-over lever after its movement has been initiated a predetermined extent, a rock shaft for initiating the movement of the throw-over lever operatively connected thereto, means whereby movement is imparted to the shaft, a manual lever controlling the operation of 100 said rock shaft to restore the valve to a normal original position after actuation.
21. In a valve mechanism as set forth, in combination, a valve casing, means for supplying a fluid from said casing to a mixing drum, a main water supply pipe connected with the upper portion of the valve casing, a measuring tank water conducting pipe leading from the casing, a valve mounted in said casing to control passage of water 105 through the casing to the mixing drum from the measuring tank, and to control passage of water from the main water supply pipe through the casing to the measuring tank, and means for operating said valve comprising a lever external to the casing connected to the valve, a throw-over lever linked to said first lever, spring means for compelling accelerated movement of the throw-over lever after its movement has been initiated a predetermined extent, a rock shaft for initiating the movement of the throw-over lever operatively connected thereto, means whereby movement is imparted to the shaft, a manual lever controlling the operation of 110 said rock shaft to restore the valve to a normal original position after actuation.
22. In a valve mechanism as set forth, in combination, a valve casing, means for supplying a fluid from said casing to a mixing drum, a main water supply pipe connected with the upper portion of the valve casing, a measuring tank water conducting pipe leading from the casing, a valve mounted in said casing to control passage of water 115 through the casing to the mixing drum from the measuring tank, and to control passage of water from the main water supply pipe through the casing to the measuring tank, and means for operating said valve comprising a lever external to the casing connected to the valve, a throw-over lever linked to said first lever, spring means for compelling accelerated movement of the throw-over lever after its movement has been initiated a predetermined extent, a rock shaft for initiating the movement of the throw-over lever operatively connected thereto, means whereby movement is imparted to the shaft, a manual lever controlling the operation of 120 said rock shaft to restore the valve to a normal original position.
23. In a valve mechanism as set forth, in combination, a valve casing, means for supplying a fluid from said casing to a mixing drum, a main water supply pipe connected with the upper portion of the valve casing, a measuring tank water conducting pipe leading from the casing, a valve mounted in said casing to control passage of water 125 through the casing to the mixing drum from the measuring tank, and to control passage of water from the main water supply pipe through the casing to the measuring tank, and means for varying the extent of movement of the last mentioned means, to control the time of operation of the rock shaft.

of water from the main water supply pipe through the casing to the measuring tank, means for operating said valve comprising a lever external to the casing connected to the valve, a throw-over lever linked to said first lever, spring means for compelling accelerated movement of the throw-over lever after its movement has been initiated a predetermined extent, and means whereby movement is imparted to the throw-over lever and means for restoring the valve to its normal position after operation thereof under the influence of the throw-over lever.

18. A valve mechanism, in combination, a valve casing, a valve in the casing, operating means for said valve including a lever external to the casing connected with the valve, means for actuating said lever to carry the valve to a predetermined operative position, and adapted to move independently of actuation of said valve, and manual means for restoring the valve to a normal position after its operation by the actuating means.

19. A valve mechanism, in combination, a valve casing, a valve in the casing, operating means for said valve including a lever external to the casing connected with the valve, means for actuating said lever to carry the valve to a predetermined operative position, and adapted to move independently of actuation of said valve, manual means for restoring the valve to a normal position after its operation by the actuating means, and operable to partially actuate the valve as a separate operation independently, of a full restoration of the valve to its normal position for the purpose set forth.

20. In valve mechanism of the class described, in combination, a valve casing, a cylinder arranged on said casing and removable therefrom, said cylinder being provided at its lower end with a valve seat, the casing having a valve seat spaced from that of the cylinder, a valve disposed in the casing and operating between the two valve seats above mentioned, a piston in the cylinder

having a connection with the valve so that the two may move together, means for holding the cylinder in place on the casing but permitting removal of the cylinder with its piston and valve, from said casing, means for operating the piston and valve parts, including connecting parts extending through the cylinder and casing, and a lever device operatively connected with the last mentioned parts for imparting proper movement to the piston and valve.

21. In valve mechanism of the class described, in combination, a valve casing, a cylinder arranged on said casing and removable therefrom, said cylinder being provided at its lower end with a valve seat, the casing having a valve seat spaced from that of the cylinder, a valve disposed in the casing and operating between the two valve seats above mentioned, a piston in the cylinder having connection with the valve so that the two may move together, means for holding the cylinder in place on the casing but permitting removal of the cylinder with its piston and valve, from said casing, means for operating the piston and valve parts, including connecting parts extending through the cylinder and casing, and a lever device connected to the last mentioned parts at a point above the cylinder and adapted to reciprocate the piston and the valve to cause co-operation of the valve with either one of the valve seats in the valve casing, the valve casing having a shoulder upon which the cylinder aforesaid is seated when assembled with said casing, a water inflow passage communicating with the cylinder between its piston and said valve, the valve casing being provided with an outflow and inflow passage, and with a separate outflow passage governed by said valve.

In testimony whereof we affix our signatures.

HERBERT R. MATSCHULL.
OSCAR FROHMAN.
